CLAIM

The ornamental design for a sleeping bag, as shown and
described.

DESCRIPTION

FIG. 1 is a top plan view of a sleeping bag showing my
new design, the bottom being plain and unornamented;
FIG. 2 is a side elevational view thereof, the opposite
side being a mirror image of that shown on the top surface;
FIG. 3 is a front end elevational view thereof;
FIG. 4 is an exploded perspective view thereof; and
FIG. 5 is a perspective view thereof.

FIG. 2FIG. 3FIG. 1
